UNITED STATES PATENT OFFICE.

BENJAMIN BRODIO, OF NEW YORK, N. Y., ASSIGNOR TO THE SUPERHEATER COMPANY, OF NEW YORK, N. Y.

WATER-TUBE BOILER WITH SUPERHEATERS.

Application filed December 29, 1925. Serial No. 78,133.

My invention relates to water tube boilers equipped with superheaters and has for its principal purpose the provision of an arrangement whereby the superheater units or elements shall be near enough to the furnace to deliver steam superheated to the high temperatures demanded to-day and yet shall be properly protected from the intense furnace temperatures and whereby at the same time the gases shall be well distributed and all of the units shall receive gases of substantially the same temperature. Other objects of the invention will appear from the following description:

15 The invention is disclosed in the drawings filed herewith in which Fig. 1 is a longitudinal section of a water tube boiler arranged according to my invention; Fig. 2 is a transverse section on line 2—2 of Fig. 1; Fig. 3 is a section similar to that of Fig. 1 illustrating a variation; Fig. 4 is a section on line 4—4 of Fig. 3; Fig. 5 is a longitudinal section of a boiler of a different type illustrating my arrangement applied to it, and Fig. 6 is a section on line 6—6 of Fig. 5 looking in the direction of the arrows.

20 I shall first refer to the form of my invention shown in Figs. 1 and 2.

25 The boiler is of the usual form and may be briefly described as follows:—

30 A front header 1 is connected to a rear header 2 by a bank of water tubes 3—3. The headers 1 and 2 may be either unitary or sectional. The front header 1 is connected to a steam and water drum 4 by means of connecting pipes 5; and the rear header 2 is connected to the same drum 4 by means of the tubes 6.

35 Below the headers 1 and 2 there are additional headers 7 and 8 respectively which may also be either unitary or sectional and which are connected to each other by means of the water tubes 9. Header 7 is connected with header 1 by means of the nipples 10, while header 8 is joined to header 2 by nipples 11.

40 Steam is taken off from drum 4 by means of the pipe 12 and led by it to the inlet header 13 of the superheater. This superheater comprises a series of tubular superheater elements or units 15, one end of each of which is connected to the header 13, the other being connected to the outlet header 14.

45 The entire boiler structure thus briefly described is enclosed in a housing A. Baf-

55 fles 16 direct the gases from the furnace 17 on their way to the stack connection 18. In the form of furnace shown pulverized fuel is to be burned, one of the burners being shown at 19.

60 The arrangement so far described is not novel. It has become common practice recently to install so called water screens in boilers, as illustrated in the present case in connection with the two side walls of the setting. The water screens shown are made of upper and lower headers 20—20 and 21—21 respectively connected by water tubes 22—22. In the present instance these tubes 22 are bifurcated. They form practically, continuous water cooled surfaces thoroughly 70 protecting the side walls. The lower headers 21—21 are supplied with water by means of the connecting pipes 23—23, which communicate with the lower header 7 by means of the nipples 24. The upper headers 20—20 are connected to the steam and water drum 4 by means of the pipes 25—25 and nipples 26. Obviously some other connections may be used for circulating water through these water screens, and the screens themselves may 80 vary in construction from that shown.

75 Water screens such as described will result in a somewhat lowered temperature of the gases leaving the furnace. In order to obtain the desired degree of superheat from the superheater it therefore becomes necessary to place the superheater nearer the furnace, that is, to interpose fewer water tubes between the superheater and the furnace than where water screens are not used. When this is done, however, there is danger that the 85 superheater elements toward the center of the furnace where the effect of the water screen is not so pronounced may be injured by the intense heat. By means of my arrangement presently to be described it becomes possible 90 to allow for the cooling experienced by the gases due to the presence of the water screen and yet properly to protect the superheater.

95 This effect is obtained by arranging the 100 water tubes which are interposed between the superheater and the furnace in a manner clearly shown in Fig. 2. In this figure there are shown two rows of water tubes in the lower bank extending clear to the side wall. There are additional rows below these two 105 but these additional rows terminate at points progressively nearer the center of the fur-

The entire boiler structure thus briefly described is enclosed in a housing A. Baf-

- nace, the result being that gases which strike 52 and 53. The details of this boiler need the superheater near the water cooled side not be further described as they do not enter walls come into contact with fewer of the into the invention. Boilers of a somewhat boiler tubes than do the gases nearer the different construction allow equally well of the center of the furnace. The inequalities in the application of my invention. 70
- 5 gas temperatures caused by the water screens are thus equalized and the temperature of the gases striking the superheater is substantially constant throughout the width of the boiler. 75
- 10 The precise number of tubes interposed near the side walls and the rate at which this number of rows is increased toward the center is of course a matter which may vary from case to case depending upon the fur- 80 nace temperatures, the degree of superheat desired, the size of the superheater, etc. The essential point in the invention is that over those areas where the gases are affected by the presence of the water screen the inter- 85 posed surface is cut down by a corresponding amount.
- 15 The side walls may also be cooled in some other way than through the presence of a water screen. They may for example be used to preheat air, such preheating resulting in a cooling of the walls and a consequent increased cooling effect on the gases near the walls. This is illustrated in Figs. 3 and 4. 90
- 20 The boiler arrangement is here substantially 95 like that of the form first described. Air for combustion is preheated in the hollow side walls entering at 30—30, flowing through the channels 31—31, and being delivered into the furnace through the openings 32—32.
- 25 The air-cooled side walls will as stated cool those gases coming into proximity to them and this is compensated here in the same way as in the first case, that is, by decreasing the 100 number of the tubes toward the side walls as compared with their number toward the center.
- 30 Even where the side walls have no water 105 screens or air ducts, the mere radiation of the side walls results of itself in a lowering of the temperature of the gases in their proximity as compared with the temperature through the body of the furnace, and my invention contemplates a similar compensation for this loss in temperature in such cases by 110 decreasing the number of water tubes below the superheater adjacent to the side walls, and as far as the cooling effect extends.
- 35 In Figs. 5 and 6 I illustrate my invention 115 as applied to a boiler with what are com- monly called upright water tubes. The boiler in this case comprises three banks of tubes 40, 41 and 42, which connect a lower drum 43 with the two upper drums 44 and 45. A 120 third upper drum 46 is connected to the drums 44 and 45 by means of tubes 47 and 48. This boiler structure is enclosed in an appropriate housing, and the gases from the furnace 49 are directed on their way to the 125 stack connection 50 by means of the baffles

front to the back of the setting and filling the space from side to side, a superheater beneath the bank comprising superheating elements distributed from one side of the setting to the other, a row of water tubes below the superheater extending from front to back and distributed from one side to the other, and additional rows of water tubes below said last named row extending from front to back and distributed over spaces terminating on each side at points progressively farther from the wall.

4. In apparatus of the class described, the combination of a boiler setting comprising a wall cooling the hot gases in the furnace coming into proximity to it, a superheater distributed through a space from the wall inward, water-cooled heat abstracting means between the furnace and the superheater so distributed that there is progressively more of it at points progressively more remote from the wall.

5. In apparatus of the class described, the combination of a boiler setting comprising two opposite walls cooling the hot gases in the furnace coming into proximity to them, a superheater distributed across the space between the walls, water tubes arranged between the furnace and the superheater their number increasing progressively toward the center.

6. In a water tube boiler, the combination of a boiler setting comprising two side walls cooling the hot gases in the furnace coming into proximity to them, a bank of water tubes distributed from one side wall to the other, a superheater comprising superheating elements likewise distributed from one side wall to the other and arranged nearer the furnace than said water tubes, and a plurality of water tubes arranged between the furnace and the superheater in such a manner that the number of such water tubes with which the furnace gases come into contact before reaching the superheater increases progressively with the distance from the side walls.

7. In a water tube boiler, the combination of a boiler setting comprising two side walls cooling the gases in the furnace coming into proximity to them, a superheater comprising tubular superheater elements distributed from one side wall to the other, and boiler tubes likewise distributed from one side wall to the other, the smaller portion of said water tubes being arranged between the furnace and the superheater and being so distributed that the number with which the furnace gases come into contact before reaching the superheater increases progressively with the distance from the side walls.

BENJAMIN BROIDO.
